(57) **CLAIM**

The ornamental design for the electronic torque wrench, as shown and described.

DESCRIPTION

FIG. 1 is a perspective view of the electronic torque wrench showing our new design, the dashed line not being part of the design;

FIG. 2 is a top plan view thereof, the dashed line not being part of the design;

FIG. 3 is a side elevational view of one side thereof, the other side being identical, the dashed line not being part of the design;

FIG. 4 is a bottom plan view thereof, the dashed line not being part of the design;

FIG. 5 is a rear end view thereof;

FIG. 6 is a front end view thereof, the dashed line not being part of the design;

FIG. 7 is a top plan view of a second embodiment of the electronic torque wrench, the dashed line not being part of the design; and,

FIG. 8 is a side elevational view of one side of the second embodiment, the other side being identical, the dashed line not being part of the design, FIGS. 4-6 being applicable to this embodiment as well.
